APPARATUS FOR AND METHOD OF
DISPENSING LIQUEFIED GASESOdd A. Hansen, Kenmore, N. Y., assignor to The
Linde Air Products Company, New York, N. Y.,
a corporation of Ohio

Application June 19, 1943, Serial No. 491,746

6 Claims. (Cl. 62—1)

1

The invention is concerned with the storing and dispensing for industrial use of highly volatile liquefied gases such as liquid oxygen. As utilized, the material is required in the form of a superheated gas at substantial pressure. Where large quantities are consumed practical considerations require the storing of the material at the consumer's plant in liquid form. Absorption of heat from ordinary atmospheric surroundings, however, rapidly vaporizes the liquid, and to avoid losses of material, or the provision of expensive equipment to cope with excessive pressures, it is necessary to store the liquid in insulated containers.

The demands for gas in industrial operations are irregular and usually intermittent with periods of shut-down which may be of considerable duration. The conditions to be met, therefore, involve the immediate availability of gas at sufficient temperature and pressure and adequate quantities to meet the maximum demands, but the avoidance of accumulation of excessive quantities and pressures during periods of lesser or no demand.

The present invention is directed to the provision of a simple economical arrangement of apparatus and mode of operation and control adapted to meet the conditions indicated in part above.

Other objects of the invention will in part be obvious and will in part appear hereinafter.

The invention accordingly comprises the several steps and the relation of one or more of such steps with respect to each of the others, and the apparatus embodying features of construction, combinations of elements and arrangement of parts which are adapted to effect such steps, all as exemplified in the following detailed disclosure, and the scope of which invention will be indicated in the claims.

For a fuller understanding of the nature and objects of the invention reference should be had to the following detailed description taken in connection with the accompanying drawing, which illustrates in diagrammatic form a system including a main container and a reserve container embodying the principles of the invention.

Referring to the drawing, two pressure containers are employed, having inner walls of sufficient thickness and strength to withstand pressures consistent with the general character of the system and the pressures desired to be maintained. The upper container comprises an inner liquid vessel 10 and an outer shell 11 providing an in-

sulating space 12 which may have a filling of suitable insulating powder, such as magnesium carbonate, and, in addition, if desired, may be evacuated of gases to provide a powder in vacuum insulating means resistant to heat transfer to an exceptionally high degree. With a powder in vacuum type of insulation the pressure increase in container 10 during idle periods is very slow and accordingly the container may be designed for lower maximum pressures and of lighter weight.

Suitable means for filling the container with liquid are provided, such as the supply line 13 having a branch 14 leading to the upper part of the container for discharging into the normal gas space, and also a branch 15 leading interiorly of the container to near the bottom thereof for discharging into the normal liquid phase. Valves 16 and 17 in the branches 14 and 15, respectively, enable selective filling of the container through either one of these branches.

Venting the container to the atmosphere may be effected through a vapor outlet 32 having therein a shut-off valve 33.

A second container is located below the one just referred to, this second container being similar in general construction and including an inner pressure vessel 60 and an outer shell 61 with a suitable insulating means 62 in the intervening space. The respective sizes of the two containers 10 and 60 may vary, dependent upon the circumstances, but in general the lower container 60 may be of less capacity than the upper one, its primary functions being that of a reserve container and converter to be operated while the upper main container is being recharged. The lower container receives its charge from the upper one, and for this purpose there is provided a gravity line 63 leading from the bottom of the upper container to near the bottom preferably of the container 60. A suitable manually operable shut-off valve 64 is embodied in this line.

Each container is provided with an automatic pressure building circuit, the circuit for the upper container comprising the line 66 leading from the bottom of container 10 through control valve 67, heater means 68 and line 69 communicating with the main withdrawal line 70. The valve 67 is made responsive to the pressure in container 10 by way of a suitable connection such as that shown at 71.

The pressure building circuit for the lower container comprises the line 73 connected to the bottom of container 60 leading from there through control valve 74, heater means 75, lines 76 and

17, back to the upper portion of container 60. Line 76 also has a continuation 78 communicating with the withdrawal line 79.

A manually operable shut-off valve 80 is located in the withdrawal line 70, 79 intermediate the connections thereto of the pipelines 69 and 78 from the respective containers. The line 79 embodies a suitable regulator valve 81 and may also include a superheater 82. The regulating valve 81 is designed to deliver gas at a predetermined pressure as, for example, 140 pounds per square inch gauge and the control valves 67 and 74 are adjusted to maintain a supply pressure a few pounds above the delivery pressure of valve 81.

In operation it may be assumed, first, that container 60 is filled and the upper container 10 partially filled, at least. At this time valves 64 and 80 will be open and gas will be withdrawn from primarily the upper part of container 10 together with such vapors as may rise through the pipelines 69 and 78. If upon continued operation the pressure in the upper part of container 10 drops below the value to which control valve 67 is set, such valve will open and circulation through the heater means 68 will serve to maintain the pressure. Since valve 74 is subjected to both the static pressure and the pressure of the added height of liquid, this valve, if adjusted for the same value as valve 67, will not open ordinarily at the same time as valve 61. If the pressure should continue to drop due to continued withdrawal of gas material, the valve 74 will open, however, permitting circulation through the coil 75. Under some circumstances the circuit through the pressure building coil 75 may be adequate to maintain the pressure and, accordingly, the pressure building circuit for the upper container comprising the line 66, valve 67, heater means 68 and pipe connections 69, may, in that case be omitted.

Assuming that the contents of the upper container 10 have been exhausted, this part of the system may then be closed off by simply closing the valves 64 and 80. With that done the container 60 and associated elements comprise a complete temporary storage and dispensing system in which withdrawal of gas will be through the line 78 initially from the gas space through the line 77, the control valve 74 opening when the pressure drops below the predetermined value for which it is set, and the withdrawal of material thereupon being for the most part through the liquid line 73 and vaporizing coil 75 which then serves the double function of a pressure building means and a withdrawal and vaporizing means for supplying the consumption apparatus.

With the container 10 now completely shut off from the dispensing system, it may be recharged in any manner suitable to conditions with appropriate equipment. The recharging method may have combined therewith suitable provision and methods for measuring the amount of the gas material added in accordance with a preferred method, the details of which are not particularly concerned in the present invention. Suffice it to note, however, that this recharging and measuring of the charge may be readily done exclusively through the container 10 and without need for making any provision for maintenance of pressure or continued supplying of gas material for consumption, since these functions will be performed in the interim by the auxiliary container 60. The arrangement in general, it will be noted, assures that the container 10 may be completely exhausted of its liquid contents be-

fore recharging is undertaken, removing any uncertainties or complications in this respect. If container 10 is being filled at atmospheric pressure with valve 33 open, valve 67 must be closed to make coil 68 inoperative.

Since certain changes in carrying out the above method and in the constructions set forth, which embody the invention may be made without departing from its scope, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent, is:

1. In apparatus for storing and dispensing gas material, the combination of a first pressure container for liquefied gas material and a second pressure container having a connection for supplying it with liquid from said first container, automatically operable means for maintaining the pressure in said containers above a predetermined value embodying a liquid line extending externally of said containers, heater means therein, and a valve connected to be responsive to pressure in said containers for controlling the flow of liquid in said line, means for dispensing gas to consumption apparatus embodying a withdrawal line connected to both of said containers, and means for shutting off said first container from said second container and the dispensing means and enabling the withdrawal thereafter of gas material solely from said second container.

2. In apparatus for storing and dispensing gas material, the combination of a first pressure container for liquefied gas material and a second pressure container arranged at a lower level having a connection for supplying it with liquid by gravity from said first container, automatically operable means for maintaining the pressure in said containers above a predetermined value, means for dispensing gas to consumption apparatus embodying a withdrawal line connected to both of said containers, means for shutting off said first container from said second container and the dispensing means and enabling the withdrawal thereafter of gas material solely from said second container, and automatically operable means for maintaining the pressure in said second container above a predetermined value during said withdrawal of gas material therefrom.

3. A method of dispensing gas material, comprising charging a main container with the liquefied gas material, connecting said main container with an auxiliary container and charging the latter therefrom, withdrawing the material for consumption while concurrently maintaining the containers in communication and under a pressure above a predetermined value, continuing such condition until the liquid contents of said main container have been exhausted, closing off said main container from the second container and withdrawal connections, withdrawing gas material thereafter from said second container while continuing the maintenance therein of said predetermined pressure by directing controlled amounts of the ma-

terial from said second container through external heating means, and recharging said first container.

4. In apparatus for storing and dispensing gas material, the combination of a first pressure container for liquefied gas material and a second pressure container having a connection for supplying it with liquid from said first container, gas dispensing means embodying a withdrawal line connected to both of said containers, a fluid circuit arranged externally to both of said containers and having a connection to the upper space of one of said containers and another connection arranged to receive liquid from one of the containers, heating means in said circuit, automatically controlled valve means in said circuit responsive directly to the pressure in said withdrawal line to control circulation through said circuit and thereby the pressure in said withdrawal line, and means for shutting off said first container from said second container and the dispensing means and enabling the withdrawal thereafter of gas material solely from said second container.

5. In apparatus for storing and dispensing gas material, the combination of a first pressure container for liquefied gas material and a second pressure container having a connection for supplying it with liquid from said first container, a fluid circuit located externally of said second container having a connection to the upper space of one of said containers and another connection arranged to receive liquid from one of the containers, heating means in said circuit, automatically controlled valve means in said circuit responsive to pressure therein to control circulation through said circuit and thereby the pressure, gas dispensing means embodying a withdrawal line connected to both of said containers, and means for shutting off said first container from said second container and the dispensing means and enabling the withdrawal thereafter of gas material solely from said second container.

6. In apparatus for storing and dispensing gas material, the combination of a first pressure container and a second pressure container having a connection for supplying it with liquid from said first container, a gas withdrawal line connectable at will with either of said containers, an external fluid circuit having a connection to the gas space of said first container and an opposite connection below the liquid level therein, heating means in said circuit, automatically controlled valve means in said circuit responsive to the pressure in said withdrawal line to control the circulation through said circuit, means for shutting off said first container from said second container and said withdrawal line and enabling the withdrawal thereafter of gas material solely from said second container, and a pressure maintaining circuit located externally of said second container and connected respectively to the gas and liquid spaces thereof and embodying in the external portion thereof heating means and automatically operable control valve means responsive to pressure in the withdrawal line to control the pressure therein when said means for shutting off the first container is made effective.
